UNITED STATES PATENT OFFICE.

JOHN B. EHRLICH, OF PORTLAND, OREGON.

HEATING APPLIANCE.

Application filed July 15, 1926. Serial No. 122,616.

This invention relates generally to the art of stove making, and particularly to a special form of stove for burning solid or gaseous fuels.

5 The main object of this invention is to provide an exceedingly simple and efficient form of stove in which the air required for combustion is pre-heated, thereby securing the most complete combustion of the 10 fuels with a corresponding decrease in the amount of smoke and soot arising from the combustion.

15 The second object is to so construct the stove that the members thereof which normally are subjected to the greatest heat—that is, the top of the fire box, are kept at a safe temperature by means of the incoming air.

20 The third object is to secure an improved circulation of air around the fire box itself, thereby improving the heating qualities of the stove without increasing the amount of fuel consumed or over-heating any of its parts.

25 The fourth object is to so construct the stove that it will lend itself to easy manufacture and that its cast iron parts can readily be converted into a furnace without in any way altering its construction other than 30 to surround same with the conventional furnace casing.

The fifth object is to so connect the drafts as to insure proper regulation of the air at all times.

35 The sixth object is to so construct the stove that it can readily be converted into a burner for coal or briquettes or for the burning of wood.

These, and other objects, will become more 40 apparent from the specification following as illustrated in the accompanying drawings, in which:

Figure 1 is a front elevation of the stove. Figure 2 is a vertical transverse section 45 through the stove. Figure 3 is a horizontal section taken along the line 3—3 in Figure 2, showing the top removed. Figure 4 is a horizontal section taken along the line 4—4 in Figure 2 with the dome removed. Figure 5 is a horizontal section taken along the line 5—5 in Figure 2. Figure 6 is a vertical section through the upper portion of the stove taken along the line 6—6 in Figure 2. Figure 7 is a side elevation of the stove showing 50 its application to a furnace casing which is

shown in cross section. Figure 8 is a horizontal section taken along the line 8—8 in Figure 7.

Similar numbers of reference refer to the same parts throughout the several views.

Referring in detail to the drawings, the stove itself consists of the usual base 10 on which is mounted an ash pit floor 11 which, in turn, supports the ash pit 12, including the ash pit door 13.

On the ash pit 12 is placed a fire box base 14 which supports the usual form of fire box 15. The usual triangular grate 16, or any other convenient type, is placed below the opening 17 in the fire box base 14. A false 70 grate 18 can be employed for wood burning, if desired. An angular lining 19 can be set against the rear wall of the fire box 15 when the false grate 18 is not employed, as when burning coal or briquettes. The combustion 75 chamber 20 is set directly upon the fire box 15, and it is in the upper portion thereof that the novel features in this stove reside.

A front 21, with the fire door 22, are also indicated, although their outward design 80 and shape will necessarily vary greatly to suit the particular requirements of the stove being manufactured.

Across the top of the combustion chamber 20 is mounted a hollow air warming baffle 85 box 23 whose under side 24 is provided with a plurality of perforations 25, whose number and size are proportional to the requirements. The rear end of the baffle box 23 is supported by the legs 26 which rest on the 90 lugs 27; while the forward edge is supported by an air inlet duct 28 whose mouth is provided with a damper 29 containing an outwardly projecting arm 30 adapted to be operated by a chain 31 and to be connected 95 by a second chain 32 to the ash pit door 13.

Over the combustion chamber 20 and its baffle box 23 is placed a dome 33, including the upper half 34 of a smoke flue 35, which latter is made integral with the combustion 100 chamber 20.

It is preferable to corrugate the members 15, 20 and 33 for the purpose of increasing the radiating surfaces and for the protection of the parts against injury due to 105 changes in temperature.

Above the dome 33 is placed a top 36 preferably provided with openings 37 for the escape of heated air.

A casing 38 is formed around the stove 110

and cold air can find its way into the stove through the open bottom of the base 10 around the ash pit floor 11.

The only difference between the form 5 shown in Figures 7 and 8 and in the figures described up to this point resides in the fact that the casing 38^A is formed somewhat circular and at a greater distance from the walls of the combustion chamber, owing to 10 the greater volume of air which the furnace must handle, cold air finding its way into the furnace casing by way of the usual cold air ducts (not shown).

It is preferable in the furnace form of the 15 device to employ a base 39 and a top 40 from whose sloping sides 41 the usual air ducts can be distributed. It is of course necessary to lengthen the smoke flue 35^A to span the greater distance between the stove and the 20 casing 38^A than exists in the stove form of the device.

In operation fuel is burned in the fire box 25 of this stove as in any other device of a similar nature, the heat from the combustion chamber rising and heating the under side 24 of the baffle box 23. Obviously, the air required for the combustion of gases within the combustion chamber 20 must enter through the perforations 25 and the control 30 of the amount of such air is entirely regulated by the damper 29. It therefore follows that all of the air required for the combustion is pre-heated, thereby totally eliminating the cooling effect which fresh air ordinarily has on a fire, and enables the temperature of the burning gases in the combustion chamber to be kept much higher than is ordinarily the case, thereby resulting in a 35 complete combustion of the fuel and a total elimination of smoke and soot from the 40 burned gases.

From this high combustion chamber temperature follows a second improved result—a greater difference in temperature between 45 the combustion chamber walls and the casing 38 of the stove itself, thereby resulting in a much more rapid passage of air upwardly

around the heated combustion chamber 20 and out through the openings 37 than would ordinarily be possible.

It is preferable to extend a flange 42 from the dome 33 to the front 21 in order that the parts will better accommodate themselves to changes in temperature without any chance of burned gases finding their way into the 55 air being warmed.

It is also preferable to provide an inner 60 wall 38^C in the stove form of the device to prevent the over-heating of the outer casing 38.

In the furnace form of the device, if the pipeless variety of furnace is to be constructed, the inner wall is merely carried up to the register and the space between same and the outer wall 38^A serves as a cold air 65 return duct.

I am aware that stoves and furnaces have long been constructed in the past; I therefore do not claim such devices broadly, but I do intend to cover all such forms and modifications thereof as fall fairly within the appended claim.

I claim:

In a stove, the combination of a combustion chamber having a dome over the top 75 thereof and having a smoke outlet projecting backwardly from the bottom of said dome; an air warming inlet projecting forwardly from the bottom of said dome; an air warming box mounted within said combustion chamber near the bottom of said dome and spaced therefrom, said air warming box having a circular form and having a somewhat concave perforated under side and a convex upper side, said warming box having an inlet duct projecting through said air warming inlet and spaced therefrom, said inlet duct having a damper therein; a damper for admitting air to the under side of the grates in the combustion chamber; and means for connecting said dampers causing same to operate in unison.

JOHN B. EHRLICH.
